INVENTOR,
Charles Eickmier
BY
J.B. Murrell
ATTORNEY.

UNITED STATES PATENT OFFICE.

CHARLES EICKMIER, OF LOUISVILLE, KENTUCKY.

FOUNTAIN-BRUSH.

1,220,506.

Specification of Letters Patent. Patented Mar. 27, 1917.

Application filed May 22, 1916. Serial No. 99,037.

To all whom it may concern:

Be it known that I, CHARLES EICKMIER, a citizen of the United States, residing at Louisville, county of Jefferson, and State 5 of Kentucky, have invented certain new and useful Improvements in Fountain-Brushes, of which the following is a specification.

This invention relates to fountain brushes intended primarily to contain liquid soap, 10 for the use of persons shaving, although it may be found applicable to other purposes.

An object of this invention, is to provide a brush of the class described which shall be facile of operation, economical and durable in service.

With the foregoing and other objects in view, the invention consists of the novel construction and arrangement of parts illustrated in the accompanying drawing, which 20 forms a part of this specification, wherein is set forth an embodiment of the invention, but it is to be understood that such changes and modifications may be resorted to as come within the scope of the claims appended 25 hereunto.

Referring now to the drawing, wherein similar reference characters designate like parts in the several views, Figure 1, is a front elevation of an embodiment of the device: 30 Fig. 2, a central longitudinal section: Fig. 3, a transverse section on line 3—3 of Fig. 2.

Referring now in detail to the drawing the reference numeral 11 designates a cylindrical shell, which forms the body, or 35 handle of the brush. In the forward end 12 of the handle, a cup-shaped member 13 is suitably secured with its open end outward forming a socket for the reception 40 of a brush 14 which is composed of bristles, or suitable material secured in a ferrule 15, and which is provided with a central tube, or conduit, 16. The ferrule carrying the brush is adapted to be 45 inserted in the cup 13, and be retained there by friction. The bottom of the socket is provided with a central perforation 17. The rear end of the handle is closed by a head 18 having a central perforation 19. An elongated cup 20 extends 50 into the interior of the handle through the perforation 19, and is provided with an annular exterior flange 21. A washer, or other suitable packing 22 is interposed between said flange and the head to form a fluid tight joint. In the bottom of the cup 20 is a central perforation 23. A valve

rod 24 which extends through the opening 17 and 23 carries on its lower end, a valve 25, adapted to close the opening 17. A plurality of guides 26 extended 60 radially from the valve-rod bear against the sides of the opening 17 and serve to center the rod. Packing 27 of any suitable material, preferably of a fibrous character, and impregnated with oil, is disposed in the 65 bottom of the cup 20, around the valve rod. A second cup 28, provided with a perforation 29 in its bottom, for the passage of the valve rod, fits within the cup 20, bearing on and compacting the packing 70 27. A coil spring 30, disposed about the valve rod, is positioned in the cup 28. This spring bears respectively against the bottom of the cup 28, and against the inner end of a stem 31 extended from a 75 thumb-piece, or button 32, which is adjustably attached to the valve rod by suitable means, such as screw-threads 33. It will be observed that the spring serves three functions, viz: It keeps the valve 25 80 85 seated and the packing 22 compressed. Pressure on the thumb-piece will open the valve, the degree of the opening, if the thumb-piece is entirely depressed, depending on the distance between the bottom of the thumb-piece and the end of the cup 26, which space may be regulated by screwing the thumb-piece on or off of the valve rod.

To prepare the device for service, it is 90 held with the brush end upward, the brush removed from the socket, the thumb piece pressed in, thereby opening the valve 25. Liquid soap, if the brush is to be used for shaving purposes, is poured through the 95 opening 17, into the interior of the hollow handle, the thumb-piece released, closing the valve and the brush replaced in the socket. To use, the bristles are first dipped in water, then the brush held downward, the thumb-piece depressed and a suitable quantity of soap allowed to flow from the reservoir, the soap finding its way into the brush through the tube 16. The brush may then be used 100 in the usual manner. After use the bristles 105 may be removed and thoroughly washed.

From the foregoing description it will be seen that I have produced a fountain brush, of convenient manipulation, and which may readily be sterilized, thus conforming to the 110 sanitary requirements of the laws of various States.

Having thus described my invention so that anyone skilled in the art pertaining thereto may make and use the same,

I claim:

5 1. In a device of the character described, a reservoir having an outlet therefrom, and having an opening opposite said outlet, a cup removably disposed in said opening, a second cup telescopically fitted in the first 10 named cup, said cups having alined perforations in the bottoms thereof, a valve closing said outlet, a rod leading from said valve through the perforations in said cups, a spring disposed about said rod within the 15 interior cup, and a thumb-piece adjustably attached to the end of the rod.

2. In a device of the character described, a reservoir, a socket positioned in one end thereof, a brush removably positioned in 20 said socket, said reservoir having an outlet into said socket, and having an opening opposite the outlet, a cup removably positioned in said opening, a second cup telescopically fitted in the first mentioned cup, said cups 25 having alined perforations in the bottoms thereof, a valve for said outlet, a rod leading from said valve through the perforations in the cups, a spring disposed about

said rod, and a thumb-piece adjustably attached to the end of the rod. 30

3. In a fountain brush, a tubular reservoir having a restricted opening at one end and an unrestricted opening at the other end, a socket positioned in the latter opening, a brush removably positioned in said socket, 35 a cup extended through said restricted opening into the reservoir, a flange on the outer end of said cup, packing interposed between said flange and the end of the reservoir, a second cup telescopically fitting in the first 40 cup, said cups having alined perforations in the bottoms thereof, packing interposed between the bottoms of said cups, said socket having an inlet from the reservoir, a valve controlling said inlet, a rod leading from 45 said valve through said alined perforations, a thumb piece adjustably connected to the outer end of said rod and a spring disposed about the rod within the interior cup and bearing respectiely on the bottom of the 50 cup and said thumb piece, said spring serving to close the valve and to maintain the cups in position relative to each other and to the reservoir.

CHARLIE EICKMIER.
